(57) CLAIM

The ornamental design for a hair remover as shown and described.

DESCRIPTION

FIG. 1 is a front, left and top perspective view of a hair remover, showing my design.

FIG. 2 is a rear, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of detail 9 in FIG. 1.

FIG. 10 is an enlarged view of detail 10 in FIG. 2.

FIG. 11 is an enlarged view of detail 11 in FIG. 3; and,
FIG. 12 is another perspective view of the hair remover shown in condition of use.

The dashed broken lines in FIG. 12 showing the handle attachment depicts environment that forms no part of the claimed design. The dot-dash broken lines are for notating enlarged portions that form no part of the claimed design. All other broken lines depict portions of the hair remover that form no part of the claimed design.
